UNITED STATES PATENT OFFICE.

JOSEPH G. SMITHERS, OF DEKALB JUNCTION, NEW YORK.

DESIGN FOR A PROTECTOR FOR BEEHIVES.

SPECIFICATION forming part of Design No. 35,700, dated February 4, 1902.

Application filed December 18, 1901. Serial No. 86,447. Term of patent 14 years.

To all whom it may concern:

Be it known that I, JOSEPH G. SMITHERS, a citizen of the United States, residing at De-
kalb Junction, in the county of St. Lawrence
5 and State of New York, have invented and
produced a new and original Design for a
Protector for Beehives, of which the follow-
ing is a specification.

This invention relates to a new and origi-
10 nal design for a protector for a beehive; and
the essential features reside in the design as
illustrated in the accompanying drawing,
wherein a perspective view of a protector em-
bodying the design is shown.

15 The design is characterized by opposite par-
allel ends 1, having the lower edges 2 straight
and the upper edges in the contour of ogee
curves, as at 3, the rear portions of the ends
1 being vertically extended and gradually de-
20 creasing in vertical extent toward their front
terminals.

The front edge of the protector is in the
form of an angular flange 4, which intersects
the front terminals of the ends 2 in planes at
right angles, the said flange having a central 25
rectangular opening 5 therein.

The top 6 of the protector is in the form of
a concavo-convex sheet following the contour
of the upper edges of the ends.

The protector is hollow and open at the bot- 30
tom and rear sides.

Having thus fully described the invention,
what is claimed as new is--

The design for a protector for a beehive, as
herein shown and described. 35

In testimony whereof I affix my signature
in presence of two witnesses.

JOSEPH G. SMITHERS.
